UNITED STATES PATENT OFFICE.

THOMAS L. STURTEVANT AND THOMAS J. STURTEVANT, OF FRAMINGHAM, MASSACHUSETTS.

VERTICAL TUBULAR BOILER.

SPECIFICATION forming part of Letters Patent No. 487,794, dated December 13, 1892.

Application filed July 11, 1892. Serial No. 439,646. (No model.)

To all whom it may concern:

Be it known that we, THOMAS L. STURTEVANT and THOMAS J. STURTEVANT, citizens of the United States, residing at Framingham, in the county of Middlesex and State of Massachusetts, have invented certain new and useful Improvements in Vertical Tubular Boilers; and we do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to improvements in vertical tubular boilers, particularly that class in which a single grate and combustion-chamber are employed in connection with two generators, one partially inclosed by the other, and so arranged that they may make steam independently, or may be allowed to act conjointly as a single steam-generating apparatus.

This invention further relates to that type of boiler called "vertical submerged flue-boilers," and may be considered as an improvement on that shown and described under application Serial No. 432,264, filed jointly by us on May 9, 1892.

The peculiar features in the present instance consist in the combination of two steam-generators, the larger one being, preferably, circular and containing the flues arranged in an annular group, while the smaller extends vertically therethrough and projects down into the fire-chamber common to both.

The invention relates, moreover, to the steam-dome which surmounts the larger generator. Thus the heating-surface is increased and the water capacity is reduced, thereby diminishing the weight of the boiler, but enabling steam to be created more rapidly from cold water, while the high-steam chamber prevents the liability to prime.

Other advantages of construction will be hereinafter explained and described.

In the drawings, Figure 1 is a front elevation of a compound boiler embodying our invention. Fig. 2 is a vertical section. Fig. 3 is a horizontal cross-section on line $y-y$ of one-half of a boiler.

In the drawings, 2 represents our submerged vertical tubular generator, composed of an exterior shell 3, an upper tube-plate 4, preferably of annular shape, and a crown-sheet 5, 55 provided with a concave or retreating cylindrical portion 6. In general shape this generator is of inverted-U shape in vertical section. The stack is shown at 7, and a fire-chamber at 8, while a series of tubes or flues 60 20 connect the top and bottom plates 4 5 and provide for the escape of the products of combustion from the fire-chamber into the stack. In connection with this tubular generator we have provided a secondary generator 9, which 65 extends centrally of the main one, but projects both above and below the latter. At the top this secondary generator is inclosed by a steam-drum 10, which surmounts the central portion of the main generator not supplied 70 with tubes, while below it extends into the fire-chamber. This secondary generator is arranged to operate independently of or conjointly with the primary generator by means of the valve 12 and plug 13, as will be herein-after explained. The lowermost part of said generator serves as a mud-drum.

To increase the size of the fire-chamber and likewise the heating surface and power of the boiler, we have formed an annular projecting 80 water-leg 14, which extends below the generator 2 and forms the walls of said chamber. The angle of this offset water-leg is such that it directs and causes the rising water to sweep across the tube-plate and tubes, thereby increasing the circulation. It is evident that a plate or partition 21, taking the place of this angle, would accomplish the same purpose. A feed-pipe 15 supplies this generator with fresh water, while a blow-off is provided at 16. The 90 central or small generator is primarily intended for salt-water and has feed and blow-off pipes, respectively, at 17 18. A plug 19 enables the pipe leading thereto to be cleansed, if necessary. Independent water-gages, try-cocks, and steam-gages are supplied in the event of the two generators being used separately.

In the operation of this boiler, we will instance that the generator 2 is supplied with 100 fresh water and that generator 9 contains salt-water. Under these conditions plug 13 is in

place and valve 12 is open, in this way permitting steam produced from the salt-water to pass into the steam-drum 10. Then fresh water is used in both, the plug 13 is removed, 5 and valve 12 opened, and feed-water is preferably supplied through the pipe 17 in order that it may become heated in the small generator 9, and there deposit its impurities before flowing into the more-complicated and 10 not-so-easily-cleaned generator. From the plain surfaces of the generator 9 scale and sediment are easily removed. The pipe 18 serves as the steam-pipe for the boiler proper, while the pipe 19 performs the same service 15 in case the generator 9 is used independently.

What we claim is—

1. The combination, with a generator having an annular group of vertical tubes, of a steam-dome surmounting that portion not supplied with tubes and an inclosed central generator adapted to extend within said dome and project below the tubular generator, substantially as specified.
2. In combination, with a vertical tubular generator and its annular offset water-leg, of the steam-dome which surrounds said generator and the generator 9 inclosed by the first and adapted to project into the fire-chamber 25

below and into the steam-dome above, substantially as stated.

3. In a steam-boiler, the combination, with a group of vertical flues, an inclosed central generator, and a steam-dome which surmounts said generator, as described, of a crown-plate provided with a retreating cylindrical portion, 35 whereby the heating-surface of both the inner and outer generators is increased, substantially as and for purposes explained.

4. A vertical tubular boiler consisting of a generator with a group of flues adapted to 40 unite the stack with the fire-chamber, a central inclosed generator, an offset water-leg which surrounds said fire-chamber, a steam-dome surmounting said generator, and a crown-sheet formed with a concave portion 45 serving as the inside wall and bottom of said water-leg, all substantially as shown and described.

In testimony whereof we affix our signatures in presence of two witnesses.

THOS. L. STURTEVANT.
